CLAIM

The ornamental design for an auricular stimulator, as shown and described.

DESCRIPTION

FIG. 1 is a right side elevational view of an auricular stimulator, showing my new design, the left side being a mirror image thereof.

FIG. 2 is a rear elevational view thereof.

FIG. 3 is a front elevational view thereof.

FIG. 4 is a top plan view thereof.

FIG. 5 is a bottom plan view thereof.
